[57] CLAIM

The ornamental design for a front control panel for a microprocessor, as shown and described.

DESCRIPTION

FIG. 1 is a front view of a front control panel for a microprocessor showing our new design;

FIG. 2 is a rear view thereof;

FIG. 3 is a top view thereof, which is a mirror image of the bottom view thereof not shown; and,

FIG. 4 is a right view thereof which is a mirror image of the left view thereof not shown.
